UNITED STATES PATENT OFFICE.

CHARLES G. WILLSON, OF READING, PENNSYLVANIA.

DESIGN FOR A SPOON.

SPECIFICATION forming part of Design No. 21,092, dated October 6, 1891.

Application filed August 27, 1891. Serial No. 403,903. Term of patent 3½ years.

To all whom it may concern:

Be it known that I, CHARLES G. WILLSON, a citizen of the United States, residing at Reading, in the county of Berks, State of Pennsylvania, have invented a certain new and original Design for Spoons, of which the following is a specification.

The accompanying drawing, which forms part of this specification, is a plan view showing the interior of the bowl and the upper surface of the handle of a spoon embodying the features of my design.

The spoon is intended more especially for a souvenir for visitors to the city of Reading, Pennsylvania. The leading features are the representation of a large pavilion of handsome design, which appears with ornamental lettering in the hollow of the bowl of the

spoon, and the ornamental lettering and scroll-work shown on the upper surface of the wider portion of the handle. It is obvious, however, that the special words shown form no part of the patentable elements of my design.

What I claim is—

The design for a spoon herein shown and described, comprising a bowl having the representation of a pavilion in the depressed surface thereof, and a handle having the shape and scroll-work thereon, substantially as set forth.

In testimony whereof I affix my signature in presence of two witnesses.

CHARLES G. WILLSON.

Witnesses:

ED. A. KELLY,
F. PIERCE HUMMEL.
